Primary Examiner — Thomas Johannes*Assistant Examiner* — Lauren McVey(74) *Attorney, Agent, or Firm* — HP Inc. Patent Department(57) **CLAIM**

I claim the ornamental design for a printer, as shown and described.

DESCRIPTION

FIG. 1 is a right side view of a printer;

FIG. 2 is a left side view thereof;

FIG. 3 is a front view thereof;

FIG. 4 is a rear view thereof;

FIG. 5 is a top view thereof;

FIG. 6 is a front perspective view thereof; and,

FIG. 7 is another front perspective view thereof.

The broken lines immediately adjacent the claim represent the bounds of the claimed design; the broken lines form no part of the claimed design.
